SQUEEGEE

William E. Kautenberg, Freeport, Ill.

Application August 26, 1939, Serial No. 292,063

4 Claims. (Cl. 15—245)

This invention relates in general to a hand operated squeegee adapted for use on windows, floors, walls and the like.

An important object of the invention is in the provision of a hand operated device in which both the cleaning element and the handle are freely adjustable for cleaning surfaces not readily accessible to fixed cleaners.

A further object of the invention is in the provision of a cleaning element of rubber or other suitable material which is freely adjustable in the holder for bringing a plurality of edges into cleaning position.

A still further object of the invention is in the provision of a flexible cleaning element having projecting ribs in connection with a holder in which the changes engage the ribs for assisting the flexing movement of the cleaner in either direction.

Still another object of the invention is in the provision of improved holding and adjustable clamping means for a surface cleaner or squeegee of this type.

Other and further objects of the invention will appear hereinafter, the preferred construction being illustrated in the accompanying drawing in which

Fig. 1 is a perspective view of a squeegee constructed in accordance with this invention;

Fig. 2 is a view of the under side of the holder as shown in Fig. 1;

Fig. 3 is a sectional view;

Fig. 4 is an end view illustrating a modified form of holder and

Fig. 5 is a sectional view showing a construction which includes a filler or cushion at one side of the service member.

Surface cleaning devices of this type are usually provided with a metal holder fixed to the cleaning element and the holder itself being rigidly attached to the handle so that the cleaning element is not replaceable and the handle is not adjustable for cleaning surfaces that are not easily accessible. The present invention overcomes these objections by providing a cleaning element which is both invertible and reversible, so that four different cleaning edges may be brought into operating position, the cleaning element may be easily replaced and the handle which is adjustable both clamps the holder in place and the cleaning element in its adjusted position in the holder.

Referring now more particularly to the drawing, a cleaning element 8 is formed of rubber or other suitable flexible material, of uniform cross

section throughout its length and having rounded ribs 9 and 10 projecting oppositely from the side faces and extending longitudinally at equal distances from the angular edges or corners 11 and 12.

To receive the cleaning element there is a channel shaped metal holder 13 with flexible or yielding sides adapted to extend over one edge of the cleaning member and having a longitudinally extending grooved rib 14 in each side adapted to receive the opposite ribs of the cleaning member adjacent the inserted edge and having an edge 15 projecting beyond the rib 14 sufficiently to engage below or to form an abutment for the other set of opposite ribs of the cleaning member which are not seated in the holder.

The edges 15 either straight, or slightly curved edges 16 as shown in Fig. 4 preferably terminate just short or free from the outer projections of 20 the cleaning member so that they will not obstruct the free insertion, removal and positioning of the cleaning member in the holder, but when the cleaning edge of the member 8 is flexed in either direction the edges 15 or 16 of the holder provide an abutment or backing for engaging the outer free ribs forming a separate and contact edge for the cleaning member throughout the full length thereof. The cleaning member normally extends at both ends beyond the holder to protect the end of the holder from becoming battered and to prevent the holder from coming in contact with articles which are being cleaned.

The cleaning member fits snugly but slidably 35 within the holder and when the handle is not clamped thereto the cleaning member may be adjusted lengthwise within the holder or it may be easily slipped out of engagement with the holder and any one of the edges 11 or 12 placed 40 in the cleaning position. The ribs 9 and 10 are located so that when the ribs 9 are engaged in the grooved ribs 14 of the holder the other ribs 10 are adapted to abut the extending edges 15 of the holder, and vice versa.

45 A metal handle socket 17 is formed with a head 18 having end notches 19 adapted to engage the holder at one side and to seat the rib 14 thereof in the notches, the edges 20 at the under side of the socket are turned inwardly for 50 strengthening it, and the socket portion has an interengaging tongue and the groove connection 21 for holding the edges of the socket member together, thereby forming a stronger reinforced head for attachment to a handle.

A clamping plate 22 is disposed at the opposite

side of the handle which has a grooved rib 23 adapted to engage the opposite rib 14 of the holder and a bent tongue 24 extending into the inner side of the handle member. A thumb screw 25 is inserted through the clamping plate and threaded into a boss or opening 26 in the wall of the socket member with the edges of the holder 13 disposed between the head 18 and the clamping plate 22 so that as the thumb screw is tightened not only is the handle member positioned in engagement with the holder, but also the opposite edges of the holder, being compressed, confine the cleaning member in any place therein in which it has been set or adjusted.

Thus the handle, the holder and the cleaning member are all easily and quickly adjusted in place, the handle may be reversed with respect to the holder thus inverting the cleaning member, and the cleaning member may be reversed and inverted in the holder when the thumb screw is loosened, the latter without removing the holder from the handle member.

Instead of providing simply one cleaning member in the holder, a cushion 26 may be inserted in one or both sides thereof, the cushion being formed of metal or rubber and preferably having grooved ribs 27 and 28 corresponding to the ribs 9 and 10 of the cleaning member and also corresponding to the ribs of the holder. In either of these forms the cleaning member and the cushioning member are engaged by the edges of the holder when they are flexed in either direction thus increasing the resilience and prolonging the wearing life and wearing qualities of the device as a squeegee and surface cleaner.

I claim:

1. In a squeegee, a channel shaped holder having a hollow rib in each of its opposite sides, a cleaning element comprising a wiping strip with longitudinal rectangular edges having a pair of opposite ribs on each side for seating it reversibly and invertibly in the ribs of the holder, the outer edges of the holder sides being normally free from but contacting either one of the outer ribs of the cleaning element depending upon which direction it is flexed, and a handle member having a clamping plate and fastening means for adjustably engaging the sides of the holder, the plate and the member having means for engaging over the adjacent inner edges and the ribs

5 at the opposite sides of the holder for adjusting the handle member longitudinally of the holder, the cleaning element and its opposite outer edges being free from the holder and said engaging means.

2. In a squeegee, a resilient cleaning element having two opposite longitudinal ribs at each side spaced equally from the edges thereof, a holder for the cleaning element comprising a channel member with opposite flexible sides and a hollow longitudinal rib in each side for slidably engaging the opposite ribs adjacent one edge of the cleaning element and permitting the reversal and inversion of the cleaning element therein, the edges of the holder projecting beyond the ribs so engaged to contact said cleaning element short of but to form an abutment for the free, opposite outer ribs of the cleaning element not seated in the longitudinal groove of the holder when the cleaning element is flexed.

3. In a squeegee, a resilient cleaning element with opposite pairs of longitudinal ribs at both sides thereof equally spaced from the opposite cleaning edges of the element, and a channel shaped holder with a hollow rib in each of the sides for extending over one edge and engaging the opposite ribs of the element adjacent either edge thereof, the edges of the holder beyond its ribs extending in the space between the ribs of the cleaning element at each side thereof and free from engagement with the outer ribs but forming an abutment for engaging one of the outer ribs when the element is flexed in the corresponding direction in the holder.

4. In a squeegee, a resilient cleaning element having pairs of ribs at each side thereof extending longitudinally and spaced an equal distance from the cleaning edges, a cushioning member having corresponding grooves and ribs disposed 10 against the cleaning element at the side thereof, and a channel shaped holder having flexible sides to compress the element and the cushion therefor and having longitudinal hollow ribs in the sides to engage the opposite ribs from one edge 15 of the cleaning element and cushion, the edges of the holder extending between the ribs of the element being adapted to engage the outer ribs of the element and cushion when the element is flexed.
